UNITED STATES PATENT OFFICE

CHARLES W. PRESCOTT, OF ROCHESTER, NEW YORK, ASSIGNOR TO GENERAL RAILWAY SIGNAL COMPANY, OF ROCHESTER, NEW YORK

RAILWAY-CAR CLASSIFICATION SYSTEM

Application filed July 16, 1925. Serial No. 43,997.

This invention relates to a railway car classification system for breaking up trains into individual or groups of cars and transferring them into the proper classification tracks from whence these cars are made up into new trains radiating in various directions.

One of the objects and purposes of the present invention is to construct a classification system which may be applied to substantially level yards without the construction of a hump and in which the various component parts thereof are controlled entirely from a tower, in which the acceleration and retardation of the cars is controlled in a manner to insure proper handling of the same, and thereby avoid injury thereto and the lading contained therein. Another object of the invention resides in the provision of car accelerating means whereby the leaving speed of a car may be selectively controlled without the employment of retarding means, and thereby economize in the energy consumption and relieve the equipment of the additional wear and tear; these purposes and characteristic features of the invention will in part be pointed out and in part be obvious from the accompanying drawings.

In describing the invention in detail, reference will be made to the accompanying drawings in which:—

Fig. 1 shows a lay-out view illustrating the relation of the various parts of a classification system embodying the present invention;

Fig. 2 shows a plan view of an approach feeder or car hauler whereby a train of cars may be gradually or intermittently fed into the classification system;

Fig. 3 is a side elevation of the apparatus shown in Fig. 2 with some of the cars omitted;

Fig. 4 is an end view of the apparatus shown in Figs. 2 and 3;

Fig. 5 is an enlarged view of the narrow gauge truck shown in Figs. 2, 3 and 4 with the cross beam in its abnormal position;

Fig. 6 is a plan view of the truck shown in Fig. 5 with the cross beam in its normal position;

Fig. 7 shows a plan view of a car retarder forming a part of the present invention;

Fig. 8 is a side elevation of the car retarder shown in Fig. 7;

Fig. 9 illustrates a guide bar forming part of the car retarder shown in Figs. 7 and 8;

Fig. 10 is an enlarged view of the guide bar shown in Fig. 9 also illustrating electrical means for controlling the pivoted switch associated therewith;

Fig. 11 shows an end elevation of the car retarder shown in Figs. 7 and 8;

Fig. 12 is an enlarged view of a link of the endless chain used in the car retarders shown in Figs. 7, 8 and 11;

Fig. 13 is a plan view of the link shown in Fig. 12;

Fig. 14 is a link and associated apparatus of a modified form of retarder, which as shown is used as a car accelerator, direction of traffic being assumed to be from left to right;

Fig. 15 is an end elevation of the apparatus shown in Fig. 14;

Fig. 16 is a wiring diagram of an automatic control system for retarding cars in a prescribed way by the retarder illustrated notwithstanding the fact that a break of cars may be loaded or empty or may consist of a single or plurality of cars;

Fig. 17 graphically illustrates the speed limit to which the automatic apparatus shown in Fig. 16 endeavors to restrict the speed of the cars, and how the retarder is accelerated so as to get out of the way of the car, near the outlet end of the retarder, the abscissa indicating the various locations of the retarder arm with respect to the point at which retardation was started during the movement of the retarder when a car passes therethrough; and

Fig. 18 illustrates an electrically operated car weight indicator and car accelerator speed indicator.

Referring to Fig. 1, the various component parts of the classification system for classifying cars, which parts are more specifically described hereinafter have been illustrated conventionally showing one arrangement as to how these parts may cooperate. It is considered expedient to first briefly point out in a general way the construction and operation

of the system embodying the present invention, without describing in detail the construction of each of the devices used in combination in this system, these various devices being more specifically described hereinafter.

General structure

Referring to the lay-out view there has been shown at the extreme left hand side a main track having an approach feeder F associated therewith, which track is connected with the accelerator lead, and which lead contains a weight bridge or car scale W and an accelerator A. From the main lead 10 diverge a plurality of classification tracks, of which the tracks 12, 13 and 14 only have been illustrated, and in the same way classification tracks diverge from the other main lead 11 of which the tracks 17 and 16 only have been illustrated. Each of the switches of the various classification leads is operated from a remote point by a switch machine SM, these switch machines being preferably of the type described in my prior application Ser. No. 23,543 filed April 16, 1925, and for convenience all of these switch machines have been assigned the same reference characters having distinctive exponents. These switch machines are controlled by levers in the tower 15, for convenience, numbered 1 to 7 inclusive.

The approach feeder F as more clearly described hereinafter includes a motor 8, whereby a train of cars may be moved forward, stopped or retarded as conditions require by an operator in the tower 15 through the medium of the controller FC, a small hump or slope preferably being provided between the approach feeder and the weight bridge W for the purpose of slightly accelerating the detached cars, so that they may be weighed during transit and may enter the accelerator A. If desired a separate accelerator similar to the accelerator A may be used instead of the hump just mentioned.

Each of the classification tracks is provided with a retarder which in accordance with the embodiment of the invention illustrated comprises two endless chains disposed on opposite sides of the track and in vertical planes. Each link of these chains contains an arm 20 which may either assume a substantially vertical inoperative position or may assume a substantially horizontal operative position, the position of these arms being determined by means more clearly described hereinafter. These various retarders are of the same construction and for convenience have been designated R¹, R², etc. These retarders R have their endless chains normally operating at a speed substantially that of the cars entering the same, and are operated so that the top parts of the endless chains move in directions as indicated by the arrows.

The car accelerator A is constructed in

substantially the same way as are the retarders R except that the motor 24¹ for operating the same is located at the exit end of the accelerator A, whereas the motors 24 for operating the retarders R are located at the entrance end of the retarders. In the particular embodiment of the invention illustrated the arms 20¹ of the accelerator A are controlled by electro-magnets 26¹ which if energized by depression of the push button 27 in the tower 15 cause the arms 20¹ to be forced into their active substantially horizontal operative position; whereas if this push button is released and energy is cut off of the electro-magnets 26¹ the various arms 20¹ of the accelerator A, as they come up over the sprocket wheel into the top horizontal plane of the chain assume their substantially vertical position in which they will not engage the pole pockets of a car standing in or moving through the accelerator A. On account of this similarity in the construction of the retarders and the accelerator the like parts of the accelerator have been given like reference characters having distinctive exponents (1).

In the tower 15 is contained a car weight indicator WI more specifically illustrated in Fig. 18 and described hereinafter which indicates to the operator the weight of each car as it passes over the scale W. The operator is also provided with a speed indicator SI which at all times indicates the speed of the accelerator A, the speed of this accelerator being variable and being controlled by the motor 24¹ through the medium of the controller AC in the tower.

Each of the classification tracks, at each retarder location as more clearly illustrated in Fig. 7, is provided with a short track circuit isolated by insulating joints 31, across the exit end of which is bridged a track battery, or other suitable source of energy 32, and across the entrance end of which is connected a track relay T. This track relay T through the medium of its front contact 33 controls a pair of electro-magnets the same as those used on the accelerator A, which magnets if energized cause the arms 20 of the retarder R to be forced into their operative positions, these magnets being energized if the truck circuit is not occupied.

General operation

Having briefly described the various devices which in combination comprise the classification system embodying the present invention, let us consider the operation of the system in a general way. The operator in the tower 15 may through the medium of the controller FC bring up a train of cars by the approach feeder F, from which train a break of cars, or a single car, may be cut loose by switchmen so that these broken off cars by reason of the small hump near the exit end 130

of the approach feeder will roll along and as they pass over the weigh bridge W the operator may sum up the total weight and he is then properly informed as to what speed the "break of cars" should be accelerated to, in order to bring them into the particular classification track into which it is to be placed at a speed so that it will at least arrive at its destination, the final speed of the car being observable by the speed indicator SI. As this car, or break of cars, has completely entered the accelerator A the operator in the tower 15 will press the push button 27, and thereby energize the electro-magnets 26 and cause the arms 20, or at least one in each endless chain, to be forced to the lower position in the rear of these cars. The operator will immediately thereafter increase the speed of the motor 24¹, so as to accelerate this car, or break of cars, to the desired speed. At the same time he, or his assistant, will control the various switch machines SM to such position as to cause the car or cars in question to take the proper classification track. Since each of the classification tracks is provided with one or more retarders R the operator at will may restrict the speed of the car or cars in question to the final required speed, this speed depending upon the direction of the wind, the gradient of the track, if any, whether the cars are full or empty and other variable conditions, such as the extent of empty track to allow the cars to reach other and standing cars on such track without dangerous impact. These retarders by reason of their electro-magnets 26 controlled by track relay T have their arms 20 assume the horizontal position so long as the track relay T associated therewith is in its energized position. As soon as a car, or cars, enters the track circuit containing this track relay T the electro-magnets 26 are de-energized and the arms 20 thereafter do not drop to the horizontal position but remain in their raised position, so that the car moving therein will cause its pole pockets (which pockets are used for pushing cars on tracks adjacent to the locomotive when car switching or shifting is carried on in the usual way) to engage the last arms 20 that have been lowered and thereby cause this car to drive the motor 24, which motor may be retarded to any desired degree by the operator in tower 15 through the medium of circuit controllers RC or by any other suitable means either manually or automatically.

From this brief description it appears that the operator in the tower can at will start a car to drift over the weigh bridge W, determine its weight, accelerate it to the desired speed dependent on its weight, cause it to take the proper classification track and then retard it to such speed as will let it roll to the end of the unoccupied track portion; this latter speed being determined from the weight of the car, condition of track, slope of the

track, direction of the wind and other factors. Having now described the operation of the classification system in a general way let us consider more specifically the construction of each of the component parts thereof. 70

Approach feeder

Referring to Figs. 2 to 6 inclusive, wherein the approach feeder F has been illustrated in detail, the approach track is provided on each side thereof with an endless pull-cable 40 which may be pulled in either direction through the medium of the pulley, winch or windlass 41 driven by a motor 8 through a chain of gears, this cable preferably being wrapped two or more times around the pulley 41 to avoid slipping. This cable 40 is supported at various points by pulleys or idlers 42 (see Figs. 3 and 4) and has its return part disposed in substantially the same horizontal plane, but is held a short distance further away from the car tracks than are these idlers 42, by large guide pulleys 43; at the extreme left hand end these cables are wound around tightening pulleys 39, which tightening pulleys are preferably adjustable. On each side of the approach track are provided two narrow gauge tracks 44, upon which the trucks 45 are adapted to run, these trucks when running on the tracks preferably straddling the main or the return approach cable 40 depending on the direction they are to move. These narrow gauge tracks are connected by switches at both ends so that the trucks 45 may be transferred from one track to the other at either end of the cable, haul, or approach feeder. 90

The trucks 45 are constructed substantially as shown, and are provided with a yoke 46 into which one end of the cross bar 47 is adapted to be pivotally fastened, as by the pin 48, the rear end of the truck being provided with an upstanding support 49 on which the other end of the cross bar 47 may rest (see Fig. 5). Directly below the yoke 46, and preferably 110 midway between the track rails on which the wheels 50 of this truck ride, is provided a projecting grooved flange 51 through which the cable 40 may freely slide if the handle 52 is in its middle neutral position. If this handle 52 is moved in a direction opposite to that in which the cable is moving, the cable grip 53 clamps the cable 40 between it and the flange 51, so as to firmly hold the cable and require the truck to move therewith, this cable grip 53 and handle 52 being fastened to a pivotally supported shaft 54 (see Fig. 6) in a manner so that the handle 53 is disposed on the outside of the narrow gauge track. 115

It should be noted that the handle 52 has a downwardly projecting end, and that near each end of the narrow gauge track is provided a post, or stop, 55, so that when the truck 45 has reached its extreme position the lower end of the handle 52 engages the stop 120

55 and causes the cable grip 53 to be automatically released. The switchmen may then pry the cable 40 off of the flange 51 and transfer the truck to the other narrow gauge track 5 where the cable may again be gripped by the cable grip and will again be automatically released when it reaches the other end of the narrow gauge track, or if desired the cable may be so aligned with respect to the narrow 10 gauge track that the cable due to side thrust disengages the cable grip as soon as the handle 52 is automatically operated.

Referring to Fig. 2 it should be noted that the cross bar 47 is provided with car couplers 58 and 59, so that if this cross bar 47 is fastened to two narrow gauge trucks moving on the narrow gauge tracks nearest the main track this bar may either push cars or pull cars, or if desired may be coupled between 20 cars and do both, push one train of cars and pull another train of cars.

In practicing the present invention as far as the approach feeder is concerned, it is contemplated that more than one pair of trucks 25 will be used, so that the second pair of trucks with their cross bar 47 may be coupled to the rear end of a train pulled by a pair of trucks ahead. With such construction when the first pair of trucks reach the exit end of the 30 approach feeder the cable is automatically unlatched and the switchmen may then disconnect the cross bar 47 at one end and swing it around on its pivot and place it in position on the support 49 as shown in Fig. 5, and the 35 other pair of trucks with their cross bar at the rear end of the train may continue to move the train without interruption. The two trucks, one of which carries the bar 47 and the other of which does not contain such 40 a bar, may then be returned to the entrance end of the approach feeder over the outside narrow gauge return tracks, and as soon as these trucks reach their destination the post or stops 55 will automatically uncouple the cable grip. The exact length of the approach cable, that is, the length of the main portion of cable 40, depends on local conditions, and may be from say 2000 to 5000 feet in length.

55

Car retarder

Referring to Figs. 7 to 13 inclusive wherein the retarder R heretofore mentioned and conventionally shown in Fig. 1, has been 55 shown in detail, the two endless chains each comprises links each link of which comprises (see Figs. 12 and 13) a chassis 60 containing four wheels 61 which are adapted to ride on the rails 62 and 63 and underneath the rails 64 and 65, and having fastened thereto four vertically pivoted wheels 66 which are adapted to ride between the rails 62 and 63 and between the rails 64 and 65, respectively. From this construction it appears that each 65 of these links is supported substantially fric-

tionless in a manner to resist severe twisting moments, which moments are present during operation of the system when such link decelerates a car through the medium of arm 20. This arm 20 engages the usual pole pocket of the car and is pivotally supported on the chassis 60 and is preferably biased by suitable means (not shown) to the inclined or substantially vertical position, as shown in Fig. 12. This arm 20 is provided with a roller 69 which rides on the rail 64 when this arm 20 assumes its active substantially horizontal position. The end of the arm 20 is provided with a resilient bumper 70 slidably secured in the end of the arm 20 and held in its normal projected position by the spring 71. A plurality of these arms are adapted to ride on the track rails 62-65 and are connected by rollerless links 73.

The retarder rails 62-65 are so positioned with respect to the classification track (see Fig. 11) that the resilient bumper engages the pole pockets usually provided on the end of freight cars; and another group of four rails, having the same spaced relation are mounted below the level of the ground on a channel 74 of concrete or other suitable material which provides an unobstructed path for the movement of the arms 20 during the underground return movement of these arms, that is, their movement after they have passed over the large sprocket wheels 75 contained at the motor end of the endless chain as more clearly illustrated in Fig. 8 of the drawings. Each of these sprocket wheels 75 contains the necessary number of sprocket teeth, which teeth are bifurcated to allow clearance for the connecting links 73.

Referring to Fig. 12 in which the arm 20 is shown in its raised biased position the tail piece 76 rides below the flange of the T-bar 77, which T-bar is more clearly illustrated in Figs. 9 and 10 of the drawings. This T-bar 77 has its entering end piece 77^a pivotally supported on a pin 78 and is normally held in its horizontal position by a spring 79, but may be held in its lower inclining position by the electro-magnet 26 acting on armature 28 when this electro-magnet 26 is energized. Also, the extreme right hand end 77^b of this T-bar 77 is securely fastened in a manner so that if the tail piece 76 has ridden above the flange of the T-bar it will be switched, so to speak, by the portion 77^b of this T-bar to the lower position in which the arm 20 is raised to its inactive position when the link reaches the extreme exit end of the retarder.

From this construction it readily appears, referring particularly to Figs. 9, 10 and 12, that the arm 20 of each roller link as it is raised upward by the sprocket wheel at the left or entering end of the retarder is held in its vertical biased inactive position, and that if the electro-magnets 26 are de-energized the tail piece 76 will enter below the flange of

the T-bar 77, so that the arm 20 will remain in its raised inactive position until it again passes over the exit end sprocket wheel into the channel 74 mounted underneath the ground. If, however, the electromagnets 26 are energized the tail piece 76 will ride on top of the flange of the T-bar 77, thereby causing this T-bar to force the arm 20 down to its dotted position (see Fig. 12), in which position if there is a car running faster than the retarder and catches up therewith the resilient bumper 70 will engage the pole pockets of the car. With the arm 20 in its active horizontal position when it reaches the portion 77^b of the T-bar 77, the tail piece 76 will again come below the flange of this T-bar 77 and thereby raise the arm 20 to its elevated inactive position. This functioning is clearly illustrated in Fig. 7 where the arms 20 near the exit end of the retarder are shown in their raised and partially raised position.

Accelerator

The accelerator A schematically shown in Fig. 1 is the same as the retarder just described, except that the motor 24¹ is located at the exit end of the accelerator, whereas in a retarder it is located at the entrance end, this in order to avoid unnecessary strains in the mechanism. Also, the control for the electro-magnets, which determine whether the arms 20 shall assume their active and inactive position is somewhat different, as already explained. For this reason the accelerator will not be specifically described and like parts have been assigned the same reference characters as for corresponding parts of the retarder except that the reference characters of the accelerator contain distinctive exponents one (1).

Modified accelerator

In Figs. 14 and 15 there has been shown a portion of a modified form of accelerator in which the endless chain rails 62, 63, 64 and 65 are somewhat differently disposed with respect to the railroad track, and in which the arm 20^a is connected to a roller wedge 20^b which contains rollers 35, 36 and 37, of which 50 the rollers 36 and 37 are insulated from arm 20^a, as shown. As heretofore mentioned the location of the pole pockets of freight cars with respect to the track rails on which such freight cars are adapted to move is substantially the same on all cars by reason of standard dimensions adopted. Also, the dimensions of the wheels of all freight cars are standardized and in accordance with a modified form of the present invention shown in 55 Figs. 14 and 15 the roller wedge 20^b may be used for engaging a wheel of a car instead of the arm 20 shown in Figs. 7 to 13 inclusive wherein the arm 20 engages the pole pocket of a car. In other words, either of 60 these forms of engaging means have been

designed so as to engage standardized parts of a freight car, so that such engagement does not interfere regardless of the type of freight car to be classified. The functioning of the modified car accelerator or retarder employing the roller wedge 20^b is substantially the same as that of the form illustrated in Figs. 7 to 13 inclusive, so that no further discussion as to its operation is deemed necessary.

Automatic retarder control mechanism

In the arrangement illustrated in Fig. 1 the speed of the retarder, or the value and direction of the torque of its motor, whereby the rate of retardation of a car by a retarder is varied, is controlled by the operator in the tower through the medium of controllers RC, but the system shown in Fig. 1 is not necessarily limited to the employment of a manual control for the retarders, and the automatic control shown in Fig. 16 may be used, if desired. The arrangement shown in Fig. 16 contemplates a checking up of the speed of the car, so to speak, at each increment of movement during its movement through a retarder, and includes means for varying the retarding force if the speed of the car is not reduced in accordance with prescribed retardation characteristics. In the particular arrangement shown, this is accomplished by the cam H or L, as conditions require, which is driven through a mutilated gear 80 which gear is biased to the normal position shown by the spring 81. This gear 80 is driven by a worm 82 connected to the shaft 83 of the retarder motor 24 through a train of gears 84, 85, 86 and 87 which are in engaging or clutched relation with this gear 80 only when the cam starter magnet 88 is energized. This cam starter magnet 88 is controlled by a circuit including a front contact 89 of a relay 90.

On the shaft 83 is also contained a speed-responsive device or centrifuge SD of the usual construction including fly balls 91 and a spring 92 for holding the fly balls near the shaft when the speed-responsive device is not rotated. Through the medium of arm 93 the speed shaft 94 assumes a rotated position depending on the speed of rotation of the shaft 83, so that the free end of the arms 95 and 95^a assume a position depending on the speed of the retarder. To the free end of the arm 95 is pivotally connected a floating lever 96, which has its free end bifurcated and containing a roller 99, which roller rides against the surface of the cam L. To an intermediate point on this floating lever 96 is pivotally secured a link 97, which has its other end pivotally secured to an arm 98 of a rheostat 100. From this it readily appears that the arm 98 of the rheostat 100 will assume a position depending on both the position of the cam L and the speed at which the retarder is op-

erated at this time. The retarder motor 24 in the particular arrangement illustrated in Fig. 16, is one of the direct current shunt type, having a shunt field winding 24^a, which field winding is connected in series with the rheostat 100. The circuit through the armature 24^b of the motor 24 is controlled by the front contact 101 of an electro-magnetic contactor (see Fig. 16) RR, this contactor RR being energized when the track relay T is energized, and when so energized connects the armature 24^b directly to a source of energy, such as a transmission line or a battery, having terminals B and C. If this contactor RR is de-energized the armature 24^b is connected directly to an energy dissipating resistance 102, as clearly shown in Fig. 16.

As heretofore mentioned, the cam L is moved in proportion to movement of the retarder, and therefore also in accordance with the progress of a car moving through the retarder, whenever the cam starter magnet 88 is energized.

Let us now consider the automatic control 23 for the cam starter magnet 88 through the medium of relay 90. In the particular type of retarder employed in connection with Fig. 16 the roller wedge 20^b engaging the tread of the wheels is employed, and in this construction the endless chains of the retarder are thoroughly grounded and connected to one side C of a suitable source of energy such as a battery; whereas the classification tracks are preferably insulated from the ground to 35 an extent to withstand, say a few volts pressure with the flow of a very small stray current. It thus readily appears that if the top roller 35 of the roller wedge is engaged by a wheel of a car a circuit for the relay 90 is completed, the cam starter magnet 88 is energized, and the cam L is operatively connected to the shaft 83 of the motor.

In order that the leaving speed of a car may be varied any number of rheostats for 45 controlling the field current may be employed and in the arrangement shown only two rheostats 100 and 100^a have been illustrated. These rheostats may be considered to be the same but are operated through cams such as 50 L and H which are preferably differently shaped as more particularly described hereinafter. The mechanism for operating the rheostat 100^a is the same as that operating the rheostat 100 except for the shape of the cam and proportioning of parts, and therefore 55 like parts have been designated by like reference characters.

Operation of retarder employing automatic control mechanism

Under normal conditions of the apparatus shown in Fig. 16 the speed of the motor 24 is automatically maintained substantially constant, and at the desired value, through the

medium of the speed-responsive device or centrifuge SD and the rheostat 100 or 100^a, depending on whether the control relay CR is energized or de-energized, this control relay CR being controlled from the tower 70 through the medium of a suitable controller RC. This automatic regulation of the speed of the motor 24, in spite of variations of line or battery voltage applied to the armature 24^b and the field 24^a, is effected by the speed- 75 responsive device SD, because if the speed of the motor 24 drops the arm 93 will turn the speed shaft 94 in a counter-clockwise direction and in so doing will cut in more resistance in the shunt field winding 24^a and thereby increase the speed of the motor, so that this speed-responsive device SD acts like a governor and tends to maintain the speed of the motor 24 constant and at predetermined value so long as the cams H and L are 80 both in their normal position.

Let us now assume that a car enters a retarder equipped with the apparatus shown in Fig. 16. As soon as the wheels and axle of this car shunt the track relay T the repeater relay RR is de-energized and the armature of the motor 24 is disconnected from the source of energy, as indicated by the letters B and C, and has its armature 24^b connected directly to the energy dissipating resistance 102, so that the motor slows down very quickly and the car catches up, so to speak, with the last arm 20^a that has assumed the horizontal position; it being remembered, that these arms continue to be 90 forced to the vertical position so long as the track relay T is energized, but do not assume such position if this track relay has once been de-energized. As soon as the car has caught up with the rolling wedge 20^b 95 the contacting of the wheels of the car with the roller 35 completes a circuit for the relay 90, and this relay 90 in turn energizes the cam starter magnet 88 and starts rotation of the cams L and H in accordance with the 100 progress of the car through the retarder. Rotation of the cams H and L depending on which one has been selected by the operator, through the medium of control relay CR which is controlled by a suitable controller 105 such as the controller RC, gradually decreases the resistance in the rheostat and thereby strengthens the field of the motor and increases the retarding force, due to the motor 24 generating current which is dissipated 110 through the resistance 102. If the speed falls in the manner prescribed by this cam H or L, the dropping of the speed cuts in more resistance and thereby reduces the retarding force. The net result is, that the car will be 115 retarded in accordance with speed-distance curves such, for instance, as shown in Fig. 17 of the drawings. If the car is to be restricted to a low speed, possibly because it is a loaded car, and for this reason the low cam L has 120

been employed, the mechanism restricts the car to the speed values such as indicated by the dotted line 110, for instance. If the car is to leave the retarder at a higher speed and for this reason the high cam H has been selected by energization of the control relay CR, the car is restricted until it has been reduced to a speed, say, as indicated by the lowest portion of the dotted line 111. If now 10 the car has practically passed through the retarder and the cam H or L, as the case may be, has almost reached its ultimate position, the roller 99^a or 99, as the case may be, drops into the notch of the cam, and thereby 15 very quickly increases the speed of the endless chain, as indicated by the inclined portions 110^a and 111^a, so that the arm of the retarder gets out of the way of the car and allows the car to proceed at this minimum 20 speed to which it was restricted by the retarder. When the arm 20^a due to the acceleration of the motor 24 has been separated from the wheel of the car, the relay 90 is again deenergized and the cams H and L are 25 stored to their normal positions, whereby the motor 24 speeds up to the initial speed heretofore mentioned at which it is controlled by the speed-responsive device ST through the medium of the rheostat 100 or 100^a as the case 30 may be.

This later feature of the automatic control mechanism, automatically causes the retarder to speed up when the car has almost passed therethrough and in so doing allows the arms 35 to be cammed up to their elevated position by the portion 77^b of the T-bar 77.

In the arrangement of the automatic control mechanism shown in Fig. 16 all of the energy absorbed during retardation is dissipated in heat, most of which is dissipated by the resistance 102. In order to conserve this energy, the motor 24 may feed the energy back into the supply line or battery, so that the braking system is, in fact, a regenerative 45 braking system, the braking energy being fed back and in turn being used for accelerating purposes. This may be accomplished by omitting the contactor RR so that the armature 24^b is at all times connected directly 50 to the distribution system. If the motor 24 is at all times connected to the line, as just explained, for the purpose of feeding the energy back into the system, the operating characteristics of the system will be somewhat 55 different than what is used to dissipate the energy through the resistance 102. It is of course understood that the cams L and H will in each case be shaped properly to cause the retarder to decelerate a car passing there- 60 through in the desired manner. Instead of starting the cams L and H when the car gets into contact with the retarder as specifically shown in Fig. 16, these cams may be started when the track circuit becomes occupied. 65 That is, if desired, the energizing circuit for

the cam starter magnet 88 may include a back contact of the track relay T instead of a front contact of the relay 90.

Weight indicator

Referring to Fig. 1 there has been shown a weight bridge or car scale W, and a weight indicator WI, which indicator as heretofore mentioned, indicates the weight of a car passing over the weigh bridge W. This weight indicator has more clearly been illustrated in Fig. 18 of the drawings. In the arrangement shown the shaft 120 assumes a position depending on the weight of the car moving over the bridge at the time, and has connected thereto a movable contact 121 which is adapted to close a pick-up circuit to one or two of the various stick relays SR depending on whether this contact 121 touches one or two of the stationary contacts 122. In the particular arrangement shown it is contemplated to store, so to speak, the indication of the weight of the last car which passed over the scale W while the push button 123 was depressed. This storing of the last selected indication is accomplished in a manner presently described.

Let us assume that there is a car on the scale which causes the contact 121 to shift to the stationary contact 122^a, and that the operator depresses the push button 123, because he wants to store the indication on the weight indicator WI. Upon depressing the push button 123, a pick-up circuit for the relay SR^a, is completed which may be traced as follows:— beginning at the terminal B of a suitable source of energy, push button 123 in its depressed position, wire 124, contacts 121 and 122^a, wire 125^a, weight indicating lamp 126^a, winding of the stick relay SR^a, wire 127^a to the common return wire C, connected to the other side of said source of energy. The energization of this circuit causes the stick relay SR^a to assume its energized position, and as the operator allows the push button 123 to again return to its raised position it completes a stick circuit for this relay SR^a, before the pick-up circuit just traced is broken. This stick circuit may be traced as follows:— beginning at the terminal B, push button contact 123 in its raised position, wire 128, front contact 129^a of the stick relay SR^a, wire 130^a, indicating lamp 126^a, winding of the stick relay SR^a, wire 127^a to the common return wire C. From this it appears that the stick relay SR^a will remain energized until the push button 123 is again depressed, in which event this stick relay will drop to its deenergized position and the stored indication is cancelled. In the same manner as just described any one of the other lamps 126 may be illuminated depending on the weight of the car on the scale at the time, and in the event that the weight is such that two of the stationary contacts 122 are contacted at the 130

same time, two adjacent lamps 126 are illuminated in which event the average weight represented by these two lamps will approximate the weight of the car. Since the several stick relays and associated indicator lamps are the same they have been assigned like reference characters having distinctive exponents. If desired, the weight indicating arm and contact 121 may be located at the weight bridge or scale, so that no mechanical transmission is required between the car scale and tower.

Speed indicator

15 For reasons heretofore given, it is found desirable to know what the speed of the car accelerator is at any time so that a car may be accelerated to the desired speed. Although any type of speed indicator whereby 20 an indication of speed may be transmitted to the tower may be used, a preferred form of speed indicator has been illustrated which as far as its indication is concerned is similar to that of the weight indicator just described. 25 This speed indicator SI includes a suitable speed-responsive device G, which in the particular embodiment illustrated comprises a centrifugal speed-responsive device which through the medium of angle lever 135 operates the speed indicating contact 131. This speed indicating contact 131 is preferably located at the motor 24¹ and is adapted to bridge the segment 132 and one or two of the stationary contacts 133, so that either one or 30 two of the various indicating lamps 134 are illuminated. In this arrangement, if two of the lamps 134 are energized the indication will be interpreted as the average speed which these two lamps separately represent. 35 Although the classification system as illustrated and as just described consists of an approach feeder followed by a hump, a weigh bridge, an accelerator in the main lead, two diverging main leads and a plurality of 40 classification tracks, located on a substantially level yard, it is desired to be understood that the invention is not limited to this specific arrangement. For instance, if there is a slight slope in the yard either tending 45 to accelerate or decelerate the cars during classification the various devices may be so designed that this grade does not materially detract from the facility afforded by this apparatus. Also, since the rate of classifications depends largely on the rate at which 50 cars can be weighed, two approach feeders each containing a weigh bridge may be employed if desired, the cars being alternately fed from one weigh bridge and then from 55 the other into the accelerator A. Also, although a slight hump has been described as being located at the end of the approach feeder F a small accelerator similar to the 60 accelerator A heretofore described may be 65 employed to separate a car, or break of cars,

from the train which is being fed up by the approach feeder to a speed suitable for weighing these cars as they pass over the weigh bridge W. Further, although the retarders illustrated have been shown as being applied to the classification tracks only it is desired to be understood that such retarders may be used on either of the two diverging main leads and that a retarder, if desired may be used in connection with a hump where no accelerator is employed, so that the speed of the car to be classified when it leaves the main lead may be controlled, or, if desired, where a small hump is present in a classification yard whereto the present invention is to be applied an accelerator may be used in connection with the hump, so that the hump alone may accelerate the heavy cars to the desired speed and the accelerator A in connection with gravity acting through the hump may be used to accelerate the lighter cars to the desired speed. In connection with these various applications of the various component parts of the present invention it is desired to be pointed out that the cars are preferably moved at a comparatively high speed through the main lead in the classification system embodying the present invention, for the reason that a certain spacing between cars is necessary in order to operate switches and in order to avoid collisions by reasons of differences in car speed, such differences being necessary to take care of heavy and light cars; and since the number of cars that can be classified is to a large extent proportional to the speed of such cars as they leave the main lead which is common to all of the tracks, it may be found expedient to accelerate the cars to a higher speed than is necessary to assure them reaching their destination. Also, the indications of weight and speed of a car as it is accelerated allow the maximum allowable speed to be attained on the main lead and therefore the best utilization of the track, and the provision of the approach cable saves the cost of a locomotive and the time of an engine crew, and saves signaling arrangements between operator and engineer.

Having thus shown and described only one specific embodiment of the invention, it is desired to be understood that the specific construction illustrated has been selected for the purpose of clearly disclosing means for carrying out the invention rather than for illustrating the particular construction preferably employed in practice, and that various changes, modifications and additions may be made to adapt the invention to local conditions where the invention is to be installed in practice, without departing from the spirit or scope of the invention or the idea of means underlying the same.

What is desired to be secured by Letters Patent is:—

1. In a railway car classification system, the combination with a main track and a plurality of classification tracks diverging therefrom, an electrically operated power driven means for engaging a car on the main track and accelerating it so that it may by its own inertia be carried into one of said classification tracks, and electrically operated regenerative car retarding means for retarding such car, said retarding means functioning in a manner to electrically store the energy absorbed during its retarding action. 5
2. In a classification system for classifying railway cars, the combination of a main track and a classification track, of means wholly on the ground and adjacent said main track for causing a car to be moved from said main track into said classification track by its own inertia, and means operated automatically and located wholly along the track for retarding said car until its speed has been reduced to a predetermined value irrespective of its own momentum and coefficient of friction. 15
3. In a classification system for classifying railway cars, the combination of a main track and a classification track, of means for causing a car to be moved from said main track into said classification track by its own inertia, means for indicating the weight of said car as the car moves in the main track, and means for storing the indication of such weight as long as desired. 25
4. In a classification system for classifying railway cars, the combination of a main track and a classification track, of means for causing a car to be moved from said main track into said classification track by its own inertia, means for indicating the weight of the car as it moves along the main track, and means for storing the indication of the weight of one car until it is desirable to observe the weight of another car. 35
5. In a classifying system for classifying railway cars, the combination of a main track and a classification track, of means controlled from a fixed tower located on the ground for causing a car to be accelerated as a result of which it is moved from said main track into said classification track by its own inertia, and means controlled from said same tower for bringing cars into the main track for classification purposes. 45
6. In a railway car classification system, the combination with a main track and a plurality of classification tracks, track switches connecting the classification tracks with the main track, switch machines for operating said track switches, car feeding means for feeding cars into said main track, accelerating means for accelerating a car so as to cause it to move by its own inertia along the main track and into one of said classification tracks, a centrally located tower, a lever for each of said switch machines
- located in said tower each of which if moved to one extreme position causes the corresponding switch machine to operate its track switch to the main track position and if moved to the other extreme position causes such switch machine to move its track switch to the classification track position, a controller in said tower for controlling said car feeding means, and a controller in said tower for controlling said accelerating means. 50
7. In a railway car classification system, the combination with a main track and a plurality of classification tracks, track switches connecting the classification tracks with the main track, switch machines for operating said track switches, car feeding means for feeding cars into said main track, accelerating means for accelerating a car so as to cause it to move by its own inertia along the main track and into one of said classification tracks, a car retarding means located in each of said classification tracks, a centrally located tower, a lever for each of said switch machines located in said tower each of which levers if moved to one extreme position causes the corresponding switch machine to operate its track switch to the main track position and if moved to the other extreme position causes such switch machine to move its track switch to the classification track position, a controller in said tower for controlling said car feeding means, a controller in said tower for controlling said accelerating means, and a controller for each of said car retarding means located in said tower, said last mentioned controllers being manually operable to vary the degree of retardation of a car when it is being retarded by said retarding means. 55
8. In a railway car classification system, the combination with a main track and a plurality of classification tracks, track switches connecting the classification tracks with the main track, switch machines for operating said track switches, car feeding means for feeding cars into said main track, accelerating means for accelerating a car so as to cause it to move by its own inertia along the main track and into one of said classification tracks, a car retarding means located in each of said classification tracks, a centrally located tower, a lever for each of said switch machines located in said tower each of which levers if moved to one extreme position causes the corresponding switch machine to operate its track switch to the main track position and if moved to the other extreme position causes such switch machine to move its track switch to the classification track position, a controller in said tower for controlling said car feeding means, a controller in said tower for controlling said accelerating means, a controller for each of said car retarding means located in said tower, said last mentioned controllers being 60
- 105
- 110
- 115
- 120
- 125
- 130

manually operable to vary the degree of retardation of a car when it is being retarded by said retarding means, and means for weighing such car during its movement on the main track.

9. A car accelerator for accelerating cars so that such cars when accelerated may by their own inertia be moved from a main track into a classification track comprising, 10 an endless chain located adjacent said main track, means for driving said chain, engaging means associated with and carried by said chain for engaging a car located upon said track, said engaging means being adapted to assume an active engaging or an inactive disengaging position, and means for moving said engaging means to its active or its inactive position during movement of such chain depending on the position the 20 endless chain is assuming at the time.

10. A regenerative car retarding system comprising, engaging means movable along the track on which the car to be retarded moves for engaging such car, and an electric generator driven by said engaging means upon engagement of said engaging means by such car, said electric generator being connected to a source of electric energy so that the electric current generated may be fed 30 into said source.

11. A car accelerator for accelerating cars so that such cars when accelerated may by their own inertia be moved from a main track into a classification track comprising, 25 an endless chain located adjacent said main track, means for driving said chain, engaging means associated with and carried by said chain for engaging a car located upon said track, said engaging means being adapted to assume an active engaging or an inactive disengaging position, means for moving said engaging means to its active or its inactive position during movement of such chain depending on the position the endless 45 chain is assuming at the time, a motor for driving said chain, and means for varying the rate of acceleration of said motor.

12. A regenerative car retarding system comprising; engaging means, movable along the track on which the car to be retarded moves, for engaging such car; and an electric generator driven by said engaging means upon engagement of said engaging means by such car; said electric generator being connected to a source of electric energy so that the electric current generator may be fed into said source; and automatic means for causing said generator to be operated as a motor when said engaging means has sufficiently retarded such car.

13. A regenerative car retarding means, movable along the track on which the car to be retarded moves, for engaging such car; and an electric generator driven by said engaging means upon engagement of said en-

gaging means by such car; said electric generator being connected to a source of electric energy so that the electric current generated by said generator may be fed into said source; and automatic means for causing said generator to be operated as a motor to move said engaging means out of the way of the car which has been retarded thereby when the speed of such car has been sufficiently reduced.

14. A regenerative car retarding means comprising; engaging means, movable along the track on which the car to be retarded moves, for engaging said car; an electric generator driven by said engaging means upon engagement of said engaging means by such car; said electric generator being connected to a source of electric energy so that the electric current generated thereby may be fed into said source; and means for varying the extent of retardation effected by said generator acting upon said engaging means.

15. A regenerative car retarding means comprising; engaging means, movable along the track on which the car to be retarded moves, for engaging said car; an electric generator driven by said engaging means upon engagement of said engaging means by such car; said electric generator being connected to a source of electric energy so that the electric current generated thereby may be fed into said source; a field winding for said generator including a source of direct current for exciting said field; and means for varying the flow of current in said field winding.

16. A regenerative car retarding means, comprising means movable along the track on which the car to be retarded moves, for engaging such car; and an electric generator driven by said engaging means upon engagement of said engaging means by such car; said electric generator being connected to a source of electric energy so that the electric current generated by said generator may be fed into said source; and automatic means for causing said generator to be operated as a motor to move said engaging means out of the way of the car which has been retarded thereby when such car has reached the end of a car retarding zone of the car retarding means.

17. The combination with a railway and a train movable thereon, of an electrical generator located adjacent a section of said railway, transmission means extended along said section and movable with the train, and co-acting means between said train and transmission means for the operation of said generator by the train momentum.

18. The combination with a railway and a train movable thereon, of an electrical power generator located adjacent a section of said railway, movable braking means located along said section, said power generator ac-

- tunable by said braking means, and engaging means between said train and braking means for retarding the speed of the train while transmitting its momentum for the operation of the generator.
- 5 19. Railway car retarding apparatus comprising an electric generator located in the trackway, and means having a part moving longitudinally along the track with the car for operating said generator.
- 10 20. Railway car retarding apparatus comprising, means movable longitudinally along the track and having a projecting part engageable by a car moving on said track, and an electric generator along the track having its shaft operatively connected to said means, whereby a car moving on said track operates said generator and generates electric current acting to retard said car.
- 15 21. Railway car retarding apparatus comprising, braking means, said braking means including an electric generator located in a certain zone adjacent a railway track, means movable longitudinally along the track operatively connected to the shaft of said generator and having a projecting part engageable by a car moving on said track, and means responsive to the entrance of a car into said zone for automatically controlling the operation of said braking means.
- 20 22. Railway car retarding apparatus comprising, a track, means movable longitudinally along the track having a projecting part engageable by a car moving on said track, insulating joints for dividing a section of said track from the rest of said track, a track circuit for said section including a track relay bridged across the rails at one end of said section and a source of current bridged across the track rails at the other end of said section, a motor for driving said longitudinally movable means in a direction so that the projecting part engageable by a car moves in the same direction as said car, and a circuit for said motor including a contact operated by said track relay.
- 25 23. Railway car retarding apparatus comprising, means movable longitudinally along the track having a part engageable by a car moving on said track for retarding such car, a shaft for at times moving said means so that its engageable part moves in the direction of such car and for at times retarding the movement of said means and a car engaging said means, and means for causing said shaft to drive said longitudinally movable means during the approach of a car and for thereafter retarding the movable means and a car engaging the same, whereby the impact of engagement of said car with said longitudinally movable means is reduced and such car is retarded upon its engagement with said movable means during its movement along the track.
- 30 24. Railway car retarding apparatus comprising, an electric generator located adjacent a railway track, means movable longitudinally along the track operatively connected to the shaft of said generator and having a projecting part engageable by a car moving on said track for electrically braking the car, and mechanism for automatically changing the operating characteristics of said generator and the degree of electric braking upon the engagement of a car with said longitudinally movable means.
- 35 25. Railway car retarding apparatus comprising, means movable longitudinally along the track and having a projecting part engageable by a car moving on said track, an electric generator having its shaft operatively connected to said means to retard said car, and means for automatically varying the retardation imposed by said generator dependent upon the speed of said car.
- 40 26. Railway car retarding apparatus comprising, an electric generator located along the trackway, means including a member engaging a car moving along the trackway for operating said generator, and manually operable means for changing the resistance of a circuit of said generator and the degree of electric braking of said car.
- 45 27. Railway car retarding apparatus comprising an electric generator located along the trackway, means including a member engaging a car moving along the trackway for operating said generator, automatic means operated by the moving car for changing the operating characteristics of said generator, and manually operable means for changing the operating characteristics of said generator, whereby the degree of electric braking of said car may be varied automatically and manually.
- 50 28. In a railway car classification system, the combination with a main track having a plurality of classification tracks, a power-operated car accelerator on the main track, means for manifesting the rate of retardation of said car, and means for retarding the car with a force depending upon the current rate of retardation.
- 55 29. In a classification system for classifying railway cars, the combination with a main track and a classification track, of means for causing a car to be moved from said main track into said classification track by its own momentum, means for retarding the car to a predetermined speed irrespective of its own momentum and co-efficient of friction, and means for indicating the speed of the car.
- 60 30. Railway car retarding apparatus comprising, means movable longitudinally along the track and having a projecting part engageable by a car moving on said track, an electric generator having its shaft operatively connected to said means to retard said car, and means for automatically varying the re-
- 65 70 75 80 85 90 95 100 105 110 115 120 125 130

tardation imposed by said generator dependent upon the momentum of said car.

31. Railway car retarding apparatus comprising, means movable longitudinally along the track and having a projecting part engageable by a car moving on said track, an electric generator having its shaft operatively connected to said means to retard said car, and means for automatically varying the retardation imposed by said generator dependent upon the current rate of retardation of the car.

In testimony whereof I affix my signature.
